New York, N. Y., a corporation of New York

Application June 9, 1945, Serial No. 598,540

9 Claims. (Cl. 197—26)

1

This invention relates to printing apparatus, and it has for a general object to provide apparatus of this type which is of improved construction and arrangement of parts and which operates effectively and at a relatively high rate of speed.

According to certain of its more specific aspects, the present invention may be considered as being in the nature of an improvement in record-controlled printing apparatus of the type disclosed in my copending application, Serial No. 492,896, filed June 30, 1943, now Patent No. 2,378,371, granted June 12, 1945. As will appear more fully hereinafter, the illustrative embodiment of the present invention includes as a part thereof the same apparatus as is disclosed in my copending application.

The printing apparatus disclosed in my said copending application comprises generally a reader, a typewriter, and control instrumentalities which function to effect automatic operation of the typewriter in accordance with data-representing designations recorded in a record strip according to a predetermined code system and successively analyzed or sensed by the reader. The data designations in the record strip represent, respectively, both the character data to be typed and the required functional operations of the typewriter such as, for example, the space, carriage-return, back-space, and tabulating operations. The reader is cyclically operable and during each operating cycle thereof the record strip is spaced to bring a data designation into sensing position, the designation is sensed, and, as a part of the sensing operation, a significant signal is produced which corresponds to the sensed designation. The reader comprises an operating shaft, termed the "reader" shaft, and each revolution of the reader shaft effects an operating cycle of the reader. The reader also includes a motor-driven power shaft, which operates continually, and also a one-revolution clutch which is effective, when engaged, to connect the power and reader shafts for one revolution and then to disconnect such shafts with the reader shaft stopping at a home position. As explained in my said application, the clutch is held engaged as long as the designations sensed represent character data or a spacing operation, the latter requiring about the same time for its completion as a character printing operation. The typewriter comprises a platen for supporting the work copy, the type bars on which the character type are mounted, and key levers corresponding, respectively, to the type bars and being selec-

tively actuatable for effecting printing on the copy sheet. The typewriter also includes key lever selectively actuatable to effect the different functional operations of the typewriter, mentioned above. A separate solenoid is connected to each of the key levers and is effective when energized to actuate its related key lever. The control instrumentalities, referred to above, include an electrical translating means which in response to each signal produced by the reader, establishes an energizing circuit for the solenoid for operating the key lever which effects the character printing operation or effects the functional operation corresponding to the designation sensed and the resulting signal produced.

An analysis of the operation of apparatus as set forth above reveals that the time required for reading the different character designations and space designations, and for producing the significant signal and energizing the proper solenoid actuator is substantially uniform for all characters; but that the time required for effecting a character printing operation varies with the different type bars and their actuating means and also varies with different typewriters, there being a substantial difference between the time required to actuate the type bar fastest to operate and that required to operate the slowest bar. Consequently, with the clutch held engaged for successive character typing operations and for spacing operations, the speed of the reader shaft must be such that the printing operation requiring the longest time for completion can be effected twice in succession. Thus, for all printing operations requiring less than the maximum time for their completion a certain part of the time allotted for the printing operation is not used.

It is a more specific object of the present invention to provide printing apparatus of the general type referred to, wherein the length of time from the beginning of each cycle in which a character designation is sensed and extending through the completion of the resulting character printing operation and to the beginning of the next succeeding cycle, varies as an increasing function of the time required for effecting such resulting character printing operation.

A further object is to provide a cyclically operable record-controlled printing apparatus wherein the time between the beginning of successive operating cycles is determined by the elapsed time required for each printing operation.

Other objects of the invention will be pointed out in the following description and claims and illustrated in the accompanying drawings, which

disclose, by way of example the principle of the invention and the best mode, which has been contemplated, of applying that principle.

In the drawings:

Fig. 1 is a plan view showing generally the units comprising one preferred embodiment of the present invention;

Fig. 2 is an enlarged fragmentary plan sectional view showing in detail the mechanical working parts of the reader, which forms a component part of the preferred embodiment shown in Fig. 1; certain of the parts being broken away to illustrate the construction more completely;

Fig. 3 is a fragmentary vertical sectional view taken on the line 3—3 of Fig. 2;

Fig. 4 is a fragmentary vertical sectional view taken on the line 4—4 of Fig. 2, and illustrating the tape feeding mechanism;

Fig. 5 is a fragmentary vertical section through the reader, the section being taken at right angles to Figs. 3 and 4 and being indicated by the line 5—5 on Fig. 2;

Fig. 6 is a fragmentary vertical sectional view taken on the line 6—6 of Fig. 2, and illustrating the clutch mechanism and its controlling magnet which function to connect the main operating shaft of the reader with a source of power;

Fig. 7 is a fragmentary vertical section taken on the line 7—7 of Fig. 3 and showing the reader pins and the manner in which they control their respective contacts;

Fig. 8 is a transverse vertical sectional view through the center of a typewriter which forms another component part of the apparatus disclosed in Fig. 1, the plane of the section being taken on the line 8—8 of Fig. 1;

Fig. 9 is a fragmentary plan sectional view showing certain details of the typewriter, the plane of the section being indicated by the line 9—9 of Fig. 8;

Fig. 10 is a fragmentary perspective view illustrating mechanism for effecting the return of the typewriter carriage;

Fig. 11 is an enlarged fragmentary vertical section showing more clearly the toggle mechanism which actuates the carriage-return clutch;

Figs. 12a and 12b are two parts of an electrical wiring diagram illustrating diagrammatically the various control instrumentalities of the apparatus and the circuit wires connecting them; and

Fig. 13 is a view showing a portion of a record tape bearing all of the code hole designations of a preselected combinational code.

Before considering in detail the construction and operation of the illustrated embodiment of the invention, it will be helpful to consider first one practical example of a preselected combinational code by means of which the character data which it is desired to print, can be recorded on a record strip or tape. In Fig. 13, a portion of a record tape 10 is shown, and punched in the tape are all of the code hole designations of a combinational six-hole code. The six code positions are indicated at both ends of the tape 10 by the reference numerals 1 to 6, inclusive, and each code designation is arranged in a vertical column or recording field, and opposite each field bearing a code designation and at the lower edge of the tape, is placed the particular character or typewriter function represented by the code designation in that field. The smaller holes 11 at the center of the tape 10 and within each of the several recording fields are for the purpose of feeding the tape lengthwise during the reading or sensing operation. The code hole designations

and the feed holes 11 may be punched in the tape by any suitable form of code perforator (not shown herein).

Referring now in detail to the construction disclosed in the drawings, it will be noted that the invention is shown as embodied in signal-controlled printing apparatus, which is shown in Fig. 1 as comprising generally a tape reader 100 enclosed within a suitable housing 12, and a power operated typewriter 200. As will appear more fully hereinafter, the apparatus also includes an electrical relay translator of the pyramid type, and certain mechanisms, devices, circuits, and other control instrumentalities which provide for the automatic operation of the typewriter under control of the code designations in the record tape 10 sensed by the reader. The translator and these other control devices, instrumentalities, etc., and their connecting circuit wires are shown diagrammatically in Figs. 12a and 12b. As will appear more fully hereinafter, these control instrumentalities are suitably mounted within the reader housing 12 and on and under the typewriter 200. The circuit wires connecting the control instrumentalities mounted in the reader 100 with those mounted on the typewriter 200 are suitably enclosed within a cable RT shown in Fig. 1.

As viewed in Fig. 1, the reader is provided across its lower side with a platform or tape table 13 across which the record tape 10 bearing the recorded data is fed step-by-step during the operation of the apparatus. A tape supply spool 15 is suitably mounted at the right-hand side of the table 13 and serves to support the record tape 10 to be read and transcribed. A second or tape storage spool 16 is provided at the left of the table 13, and, as will later appear, is rotated by a flexible belt 17 during operation of the apparatus, for the purpose of winding the tape thereon after it leaves the sensing station of the reader. The sensing station is indicated at 20 and, as will appear more fully hereinafter, the recording fields of the tape are successively sensed during successive operating cycles, by sensing elements located at the station 20. A removable gate 21 is provided at the sensing station for properly positioning and holding the tape with respect to the sensing elements. The tape 10 is guided in its movement toward the sensing station by a suitable guide member 22 fixed to the top of the tape table 13.

At the right-hand side of the reader 100 as viewed in Fig. 1, are provided three electrical switches indicated, respectively, at 24, 25, and 26. As will appear more fully hereinafter, the switch 24 is the power switch and when closed, connects a convenient source of alternating current with a motor for driving the reader unit and with a motor for operating the typewriter. The reader motor is indicated by the character RM in Figs. 2 and 12a, and the typewriter motor by TM in Fig. 12b. The switch 25 is the start switch and when operated starts the sensing and feeding of the tape and the automatically controlled operation of the typewriter key members. The switch 26 is the stop switch and when closed instantly stops the feeding and sensing of the tape and the controlled operation of the typewriter.

The typewriter 200 which is shown in plan in Fig. 1 and the detail construction thereof in Figs. 8, 9, 10, and 11 will be recognized as being a well known commercial form of power-driven typewriter and will be described more fully here-

inafter. In Fig. 1, the typewriter 200 is shown as comprising a keyboard 210 including the required complement of character keys 211 which operate corresponding type bars 212, and the functional keys which include the shift key 213, shift lock key 214, shift release key 215, the carriage return key 216, the back space key 217, and the tabulating key 218. The space bar is indicated at 223. The typewriter 200 also comprises the conventional rotatable platen 219 mounted on the typewriter carriage 220 and which supports a copy sheet indicated at 221 and on which the data recorded in the tape 10 are automatically typed.

At the lower and left-hand side of the typewriter as viewed in Fig. 1, is provided a power switch 224 which, when closed, like the power switch 24, connects a source of alternating current with the typewriter and reader motors. At the lower and right-hand side of the typewriter is mounted a start switch 225 and a stop switch 226 which function, respectively, the same as the switches 25 and 26 on the reader 100. Thus, the operation of the apparatus may be controlled from either the typewriter or from the reader. An insert switch 227 is also provided on the typewriter which, when open, prevents starting of the tape feeding and sensing mechanisms in the reader 100 and thereby eliminates control by the latter of the typewriter, so that the keys of the typewriter keyboard 210 can be operated manually without interference from the reader. The insert switch 227 will normally be closed, and will be opened when it is desired to type manually an insert in the data being transcribed; for example, when it is desired to type manually the name and address of the person to whom the transcribed copy is to be sent or any other data which will be of interest only to the recipient of the copy.

The detail construction of the reader is shown in Figs. 2 to 7, inclusive. The reader comprises the reader motor RM which is suitably mounted within the housing 12 and which operates continuously as long as either the power switch 24 or power switch 224 is closed. The motor is at all times operatively connected by a suitable flexible drive belt 30 with a power shaft 31, the latter being mounted for rotation within suitable bearings 32 mounted within a frame 33 which is bolted to the base 34 of the reader.

The reader 100 also comprises an operating shaft 35 which is aligned with the power shaft 31 and is supported for rotation within suitable bearings 36 carried by the reader frame 33. The shaft 35 is referred to herein as the "reader" shaft. A clutch 37, under the control of a clutch magnet CM, is operable to connect and disconnect the reader shaft 35 and the power shaft 31. The reader shaft effects the operation of the tape feeding and sensing means.

A cycle of operation of the apparatus is effected during each revolution of the shaft 35; viz., the tape 10 is fed or spaced a distance sufficient to bring the next recording field of the tape into sensing position, such next field is sensed to determine the code designation therein, if any, and the typewriter is operated in response to the sensing of the code designation. As long as the shafts 31 and 35 are clutched together the cycles of operation are repeated and the typewriter continues to transcribe the data recorded in the tape being read.

In so far as the present invention is concerned, any suitable form of clutch may be used to con-

nect the reader shaft 35 to the continuously operated power shaft. The clutch 37 which is shown, is well known to those skilled in this art, it being substantially the same as that disclosed in the U. S. Patent No. 2,206,646, granted July 2, 1940. If desired, reference may be had to said patent for a complete showing of the structural details thereof. For the purposes of the present disclosure, it is believed sufficient to say that the clutch comprises a driving element in the form of a toothed wheel 40 fixed to the end of the power shaft 31, and a driven element in the form of a barrel 41 fixed to the reader shaft 35 and carrying a radially slidable clutch pawl 42. The barrel 41 is formed with a diametrically disposed slot 43 within which the pawl 42 is slidably mounted. To the outer end of the pawl 42 is fixed a tooth element 44 which, when the pawl 42 is moved radially inward, engages the toothed wheel 40 to provide the driving connection between the shafts 31 and 35. The pawl 42 is biased in a clutch engaging direction by a suitable spring mounted within the clutch barrel 41. A clutch releasing lever 45 also extends diametrically across the clutch barrel and at right angles to the slot 43 and is mounted for limited angular movement therein. The lever is provided with an outer extension 46 which, when intercepted and engaged by the outer end of one arm 47 of a rocking lever 48, is moved to move the clutch pawl 42 radially outward against the force of the aforementioned spring in the barrel 41 to disengage the clutch.

The clutch parts are shown in Figs. 2, 5, and 6 in their declutched position which is the home or starting position of the reader. The rocking lever 48 is mounted on a stud 50 carried by a part of the frame 33 and includes a second arm 51 which carries at its outer end the armature 52 of the clutch magnet CM. When the clutch magnet CM is energized, the lever 48 is rocked counterclockwise, as viewed in Fig. 6, which moves the outer end of the arm 47 upward and thereby releases the outer extension 46 of the releasing lever 45, and the clutch spring within the clutch barrel 41 then moves the pawl 44 radially inward to engage the toothed wheel 40 in the manner explained above. When the clutch magnet CM is deenergized, a tension spring 53 rocks the lever 48 clockwise and moves the outer end of the arm 47 into the path of the outer extension 46 of the lever so that the latter is engaged and moved to move the pawl outward to disengage the clutch.

In order to prevent rebound of the parts when the clutch is disengaged and in order to hold the reader shaft 35 in the home position, the clutch barrel 41 is also provided with an annular extension or collar 54 having a notch 55 formed therein which, when the clutch is disengaged, receives the outer end of an arm 56 of a detent lever 57. The detent lever 57 is also pivoted on the stud 50 and includes another arm 58 which is connected to the armature 52 by means of the tension spring 53 previously mentioned. Thus, the spring 53 serves the dual purpose of urging the arm 56 into engagement with the periphery of the collar 54 so that it will fit within the notch 55 in home position, and of urging the arm 47 into position to intercept the extension 46 of the pawl releasing lever 45 and thereby declutch the parts.

As stated above, during the first part of each revolution of the reader shaft 35, the tape is fed or spaced lengthwise to bring a new recording field into sensing position. The tape feeding mechanism is shown more clearly in Figs. 2 and 4, and

comprises a cam 60 mounted on the reader shaft 35 and cooperating with a rocking lever 61 pivoted on a fixed stud 62 carried by the frame 33 and comprising a pair of arms 63 and 64. The cam 60 and lever 61 are shown in Fig. 4 in the starting or home position and are so constructed that when the cam 60 begins to rotate in a counter-clockwise direction, it first engages the arm 63 to rock the lever 61 counterclockwise and then engages the other arm 64 to rock the lever 61 clockwise and return the same to the position shown. A link 66 is pivoted at its lower end to the outer end of arm 64 and extends upwardly therefrom and is pivoted at its upper end by a stud 67 with a second link 68. The link is also pivoted to a shaft 70 and serves to hold the link 66 in its upright position shown.

Also pivotally connected on the stud 67 is a feed pawl 71 which is held in operative engagement with a ratchet wheel 72 fixed to the shaft 70, by means of a tension spring 73 connecting outer extending arms of the pawl 71 and the link 68. A detent 74 is pivotally supported by a fixed stud 75 and is held in engagement with the teeth of the ratchet wheel 72 by means of a tension spring 76 and thereby serves to prevent reverse movement of the ratchet wheel 72 and shaft 70. From the above, it is apparent that when the clutch 37 is engaged to rotate the reader shaft 35 and when the lever 61 is first rocked counterclockwise by the cam 60, the pawl 71 will be moved downwardly thereby and will rotate the ratchet 72 and shaft 70 counterclockwise; and, when the cam 60 rocks the lever 61 clockwise, the pawl 71 will be moved upward to engage the next tooth of the ratchet 72.

The shaft 70 is the tape feed shaft and is provided with a feed wheel 77 having radially extending pins 78 which are adapted to engage the feed holes 11 in the tape 10. Thus, when the feed shaft is partially rotated in the manner just described, the tape is fed to the left as viewed in Figs. 1 and 2, a distance equal to the width of a recording field. The belt 17 which rotates the spool 16 shown in Fig. 1, is driven from a pulley 79 fixed to the tape feed shaft 70.

The mechanism for successively sensing the recording fields of the tape comprises six sensing pins indicated, respectively, by the characters S1 to S6, inclusive. There is one pin for each of the code hole positions and the pins are arranged in a single vertical plane extending at right angles to the direction of movement of the tape, and so that when the tape comes to rest at the end of a feeding operation, the upper end of each pin will be directly beneath its corresponding code hole position in the field of the tape then in position to be sensed. The pins are guided for vertical movement within aligned openings in spaced guide blocks 80 and 81, respectively, which are suitably fixed to the frame 33. Aligned pairs of guide openings are also provided in the table 13 and in the gate 21 and they are aligned with corresponding openings in the guide blocks so that during a sensing operation each pin can be moved upward and through the tape when there is a hole in the code position in the tape corresponding to such pin.

The six sensing pins are supported and operatively connected, respectively, at their lower ends to six pairs of spring blade contacts indicated, respectively, by the characters C1 to C6, inclusive. Each pair of contacts comprises an upper fixed blade 82 and a lower movable spring blade 83 which extends outwardly beyond the

end of its related fixed blade and is connected at its outer end to the lower end of its related sensing pin. The construction is such that the spring blades 83 constantly urge their respective contacts upward into closed position and their related sensing pins upward as viewed in Figs. 3 and 7. Between sensing operations, the six sensing pins are held in home position, the position shown in Fig. 3, by the outer lateral edge 84 of a vane 85, which edge extends across all of the pins and within transversely aligned notches 86 provided, respectively, in the sides of the pins. The vane 85 is, in effect, a rocker arm pivotally supported on a rod 87 carried by the frame 33 and constantly urged to move in a clockwise direction, as viewed in Fig. 3, by a tension spring 88. The vane 85 is provided at its center with a depending arm 89 which carries at its lower end a roller 90 held by the spring 88 in contact with the face of a cam 91 mounted on the reader shaft 35. When the roller 90 is in engagement with the high point of the cam 91, the vane 85 is held in the position shown in Fig. 3 where the several sensing pins are held in their respective lower positions and the pairs of contacts controlled thereby are held open.

After the tape has been spaced by the feeding mechanism in the manner previously described and has come to rest with the new recording field above the sensing pins, the shaft 35 and cam 91 will have rotated counterclockwise from the position shown in Fig. 3, 94° of a revolution. When the shaft 35 has rotated 114°, the roller 90 will begin to move inwardly from the high point of the cam 91, and the vane 85 will move in a clockwise direction due to the force of the spring 88. The sensing pins S1 to S6, inclusive, will also follow the end 84 of the vane 85 upward due to the spring force in their respective movable blades 83. If there be a hole in the code position of the tape immediately above a sensing pin, its movable spring blade 83 will continue to move the pin upward and through such code hole and to a point where the pair of contacts controlled thereby will close. If there be no code hole in the position above a sensing pin, the upper end of such pin will strike the tape 10 and will be held thereby against further upward movement, and in the latter position its related pair of contacts are held open.

By way of example, Fig. 7 shows the relative position of the parts during the sensing of a record field bearing the 1-3-5 code designation, which as shown in Fig. 13 represents the letter character "Y." Sensing pins S1, S3, and S5 are shown as having passed through code holes in the corresponding code positions 1, 3, and 5 in the tape 10 and their related contacts C1, C3, and C5 are shown closed. The sensing pins S2, S4, and S6 have been stopped in their upward movement by the tape and their related contacts C2, C4, and C6 are thereby held open.

From the foregoing, it is apparent that during a sensing or reading operation the contacts C1 to C6, inclusive, are closed by their related sensing pins singly or in combination, depending upon the code hole designation in the record field of the tape being sensed. The sensing operation is terminated by the high point of the cam 91 engaging the roller 90 on the arm 89 and moving the vane 85 counterclockwise, as viewed in Fig. 3, so that the end 84 thereof engages again the lower ends of the notches 86 in the several sensing pins S1 to S6, inclusive, and thereby moves the latter downward to the position shown in Fig. 3, where

the related contacts are held in open position. The sensing operation is completed and the vane 85 is restored to home position at approximately 346° of each revolution.

In order to provide for automatically stopping the reading or sensing operation when there is no tape at the sensing station, a seventh pin 94 is mounted for vertical sliding movement within aligned openings in the spaced guide blocks 80 and 81 and in the table 13 and the gate 21 and is positioned so that it will engage the central portions of the tape. The lower end of the pin 94 is supported and operatively connected to the movable spring blade 95 carrying one of a pair of contacts 96. The blade 95 is normally urged upward by the spring force inherent therein, to open the contacts 96 and move the pin 94 upward. If there is a tape at the sensing station 20, the upper end of the pin 94 engages the underside of the tape and the contacts 96 are held closed. This is the position of the parts shown in Fig. 7. When the tape runs out, the pin 94 moves upward and opens the contacts 96 which, as will appear later, opens the energizing circuit for the clutch magnet CM and thereby stops the feeding and sensing operation of the reader. In Fig. 3, no tape is shown at the sensing position 20 and the pin 94 is shown in the upper position where the contacts 96 are open. The pin 94 is made sufficiently large in diameter so that the feed holes 11 in the tape 10 will not affect its operation.

Each sensing or reading operation produces a significant signal corresponding to the designation sensed. As will be explained more fully hereinafter in connection with the description of the wiring diagram shown in Figs. 12a and 12b, the sensing contacts C1 to C6, inclusive, control respectively, the flow of direct current within six signal circuits, the latter including, respectively, six translator relays M1 to M6, inclusive, of a relay type of translator mechanism which, as stated, is diagrammatically shown in Fig. 12a. At this point it is sufficient to say that by energizing translator relays M1 to M6, inclusive, singly and in combination, due to the selective closing of their related contacts C1 to C6, inclusive, during the reading operation described above, a number of controlling circuit paths through the translator are selectively established, which circuit paths correspond, respectively, to the code designation sensed. With certain exceptions hereinafter explained, each of these circuit paths, when closed, actuates a related key member of the typewriter 200.

A cam 102 is also fixed to the reader shaft 35 and controls through a pivoted follower 103, the operation of a pair of spring blade contacts 104. As will appear more fully hereinafter, the contacts 104 control the flow of signal current from a suitable D. C. source and through the contacts C1 to C6, inclusive, in parallel, to their related translator magnets M1 to M6, inclusive. The contacts 104 may be termed the D. C. common contacts and are normally held open by their movable spring blade. The cam 102 is so shaped and positioned on the operating shaft 35 that the contacts 104 are closed at 142° of a revolution which is after the time for closing the sensing contacts C1 to C6, inclusive, and are opened at 311° which is before the sensing contacts are opened by the vane 85. The purpose of the D. C. common contacts is to provide for simultaneously energizing and deenergizing the translator relays M1 to M6, inclusive.

A cam 106 is also fixed to the reader shaft 35

and controls through a pivoted follower 107 the operation of a pair of normally open spring blade contacts 108 which are herein termed the A. C. common contacts. As will appear more fully hereinafter, the current which flows through the controlling circuit paths of the translator previously mentioned as being conditioned by the selective energization of the translator relays M1 to M6, inclusive, is A. C. current, and the cam 106 is so shaped that it connects the source of A. C. current with these circuit paths at a predetermined point in each cycle of operation. In the structure shown, the cam effects the closing of the A. C. common contacts 108 at approximately 170° of each revolution and opens the contacts at 294°. The detail construction of the typewriter is shown in Figs. 8, 9, 10, and 11 and as stated previously, is a well known commercial form of power driven typewriter. The structural features and principles of operation of this typewriter are fully disclosed in a number of U. S. patents, among which are Patent No. 1,777,055, granted September 30, 1930, and Patent No. 1,873,512, granted August 23, 1932. These 20 patents disclose the general principles of operation of the key levers and how they control through related cam units, the operation of the type bars, and the manner of spacing the typewriter carriage. In view of the detailed description 25 of the construction and operation of the parts given in the patents just mentioned, only a brief description will be given herein which will be sufficient to enable the present invention to be understood. Reference may be had to the aforementioned patents for further details.

As shown in Fig. 8, the character keys 211 are mounted, respectively, on key levers 228, the latter being pivoted on a rod 229 which is supported by a cross frame 230 rigidly mounted in the typewriter frame. Rotatably mounted in the base 231 is the power roller 232 which is rotated in the direction of the arrow by means of an A. C. motor, not shown in Fig. 8, but indicated diagrammatically at TM in Fig. 12b. When the machine is in use, the power roller rotates continually.

Cooperating with the power roller 232 are the cam units 233 which are pivotally mounted on rods 234 extending parallel with the power roller 232. There is a cam unit 233 associated with each of the key levers 228, and each of the cam units which is operated by a character key 211, is connected by a link 235 with a sub-lever 236 pivoted on rod 229. The sub-levers 236 are connected by links 237 to type bars 212 through the medium of toggles 238. The type bars 212 are pivoted in the usual type bar segment 239 and the latter is provided with a type guide 240 located in front of the platen 219. As stated previously, the platen is adapted to support the work sheet 221 and is rotatably mounted in the carriage 220, and the latter is supported for lengthwise movement on front and rear rails 241 and 242, respectively, by means of suitable anti-friction roller trucks. Springs 243 connected to a curved spring anchoring member 244 and to toggles 238, provide means for locking the toggles in their normal or inactive position shown in Fig. 8.

When any character key 211 is manually depressed, its related cam unit 233 is caused to operatively engage the power roller 232 in a well known way, thereby rocking the cam unit 233 clockwise or counterclockwise, according to whether the operative cam unit is pivoted on the

left hand or right hand rod 234, respectively, as viewed in Fig. 8. The rocking of the cam unit 233 causes its link 235 to be drawn downward, thereby rocking the corresponding sub-lever 236 in a clockwise direction. This movement of the sub-lever 236, through the corresponding link 237 and toggle 238, causes the type bar 212 associated with the selected key to rock in a counter-clockwise direction to effect the impression of the type upon the work sheet 221 wrapped around the platen 219. The type bar, near the end of its operating stroke, engages the usual universal bar 245 and causes the universal bar to move rearwardly and downwardly as viewed in Fig. 8 to space the carriage forward in a manner which is not disclosed in detail herein, but which is fully disclosed in the above mentioned Patent No. 1,873,512 and is well known to those skilled in this art.

To each of the character key levers 228 is connected by a spring 246, an electrically responsive actuator in the form of a solenoid 247 which, when energized, pulls its related key lever 228 downward to operate the related cam unit 233 and type bar 212 in the same manner as described above when the related key 211 is manually depressed. As will appear more fully hereinafter, the solenoids 247 are selectively energized by the A. C. controlling circuit flow paths previously mentioned as being selectively established by the energizing of the translator relays M1 to M6, inclusive.

As will be readily understood by those skilled in the typewriter art, one of the cam units 233 is operated by manually depressing the space bar 223 and its related key lever, and such cam unit when operated effects the rearward movement of the universal bar 245 to space the carriage as is fully disclosed in the above mentioned Patent No. 1,873,512. The detail linkage and mechanism for effecting this operation has not been shown herein as it would be a needless duplication of drawings and description. An actuator in the form of a solenoid 247 is also provided for operating the key lever in which the space bar 223 is mounted. The latter solenoid is shown diagrammatically in Fig. 12b.

The type bar segment 239 is mounted in a frame 248 and both the segment and the frame form parts of the type basket. The type basket is movably mounted in the framework of the machine for case shifting movement in a well known way and normally occupies an elevated position shown in Fig. 8 for the typing of lower case characters referred to hereinabove. In Figs. 1 and 8, only one of the type bars 212 has been shown. The lower case type element on the bar 212 is indicated at 212a and the upper case type element at 212b. The case shifting mechanism for drawing the type basket downward to permit the printing of shifted case characters is fully disclosed in U. S. Patent No. 1,945,097, granted January 30, 1934, and consequently need not be shown in detail herein, it being sufficient for the purposes of the present disclosure to note that each time the shift key lever 250 (Fig. 1) is moved downward by a solenoid 247 or by manually depressing key 213 or key 214, a cam unit engages the power roller 232 and the type basket is moved downward to its upper case position, and each time a shift-release key lever 251 is moved downward by a solenoid 247, or by depressing key 215, the type basket is moved upward and returned to its lower case position. A full disclosure of the case-shifting mechanism

is also included in my copending application referred to herein at the outset.

The mechanism shown herein for returning the carriage to begin a new line of typing is well known to those skilled in the typewriter art. Attention is directed to U. S. Patent No. 2,104,559, granted January 4, 1938, and U. S. Patent No. 1,753,450, granted April 8, 1930, for a full disclosure of the structural details of the carriage return mechanism shown herein, the later granted patent being directed to the specific clutch shown herein for connecting the power roller to the drum about which the carriage return tape is wound.

Referring to Figs. 10 and 11, the carriage return key 216 is shown as mounted on a key lever 252 pivoted on the rod 229 and controlling the operation of a cam unit 253 which is similar in construction and operation to the previously described cam unit 233. One of the solenoids 247 is connected by a spring 246 to the key lever 252 and when energized, moves the key lever downward to effect operation of the cam unit 253. The latter is connected by a link 255 with the inner or left-hand end of a toggle lever 256 pivoted on a fixed stud 257 carried by a bracket 258 which is secured to a part 259 (Fig. 11) of the frame of the typewriter. The outer or right-hand end of lever 256 is connected by a toggle link 260 (Fig. 11) to one arm of a two-part lever 261 pivoted on a pin 262 which is carried by the lower end of a bracket 263 fixed on the typewriter frame part 259. Another arm 264 of the two-part lever 261 is disposed adjacent a clutch 265. As described fully in Patent No. 2,104,559, when lever 261 is rocked clockwise, as viewed in Fig. 11 herein, the clutch 265 connects the power roller 232 with a drum 266 about which one end of a carriage return tape 267 is wound. The other end of the tape 267 is connected to a part of the typewriter carriage 220.

When the cam unit 253 is operated, either by energizing the solenoid 247 or by manually depressing the key 216, the lever 256 is rocked counterclockwise as viewed in Fig. 11, and the toggle formed by the right-hand arm of lever 256 and the link 260 is straightened and thereby effects the just mentioned clockwise movement of the two-part lever 261 to engage the clutch 265. The lever 256 is moved by the link 255 slightly past the dead center position of the toggle and thus the lever 256 and the associated parts are held in the clutch engaging position. Upon engagement of the clutch 265, the carriage 220 will be returned, i. e., moved to the right as viewed in Fig. 10, to begin a new line of typing.

At the same time the lever 256 is moved to engage the clutch in the manner just described, the inner or lefthand end of the lever 256 engages and moves downward one arm 269 of a bell crank 270 which is suitably pivoted by a pin 271 to a fixed part 272 of the typewriter frame. The bell crank 270 will thus be moved about its pivot pin and a second arm 273 thereof, through a connecting link 274, will move a lever 275 pivotally mounted on a pin 276, clockwise about its pivot; and the lever 275 through a link 277 will move a lever 278 which is pivoted on a pin 279 carried by the rail 242, counterclockwise about its pivot. The lever 278 is formed with an arm 281 which when moved counterclockwise in the manner just stated, will be positioned within the path of travel of the left-hand marginal stop 282 of the typewriter.

The stop 282 is mounted on a rack bar 283 carried by the typewriter carriage, and can be positioned thereon at any selected point corresponding to a letter space position of the carriage. Near the end of the return movement of the carriage and just before the marginal stop 282 engages a fixed lug 284, formed on a part (not shown) of the tabulating mechanism, to stop the carriage, the marginal stop 282 engages the top surface of arm 281 and thereby rocks the lever 278 clockwise. When the lever 278 is thus moved clockwise, motion is transmitted through the link 277, lever 275, and link 274, to rock the bell crank 270 so as to move its arm 269 upward to engage the lever 256 and thereby move the latter clockwise to break the toggle and move the two-part lever 261 counterclockwise which will effect disengagement of the clutch 265 and thereby disconnect the power roller 232 from the tape drum 266.

As indicated in Fig. 10, the carriage return cam unit 253 is provided with a downward extension 285 carrying a contact operating roller 286 which engages a movable spring blade 287 of a contact assembly 288 suitably mounted on the typewriter. The assembly 288 comprises a pair of make contacts 290 a pair of break contacts 291, and a second pair of make contacts 292. The spring blade 287 is connected by an insulated post 293 with movable blades 294 and 295 of contacts 291 and 292, respectively. When the cam unit 253 is operated in the manner previously described, the roller 286 shifts the blade 287 and blades 294 and 295 downward to close contacts 290 and 292 and open contacts 291. While the carriage 220 is returning, the toggle lever 256 holds the cam unit 253 in the shifted position and the latter holds the contacts in their actuated position, just described. When the carriage returns to the point for beginning a new line of typing and the toggle is broken by the arm 269, the cam unit 253 returns to its normal position, shown in the drawings, and the blades 287, 294, 295 move to return the contacts controlled thereby to their normal position shown. The purpose of the contacts mechanically operated in the manner just explained by the cam unit 253 will be described more fully hereinafter in connection with the wiring diagram in Figs. 12a and 12b.

The other functional operations of the typewriter disclosed, such as back space and tabulating, are effected in a manner which is also well known to those skilled in this art. Consequently, a detail disclosure herein of the mechanisms for effecting these operating functions is considered unnecessary. They are disclosed fully in my said copending application and in prior United States patents identified therein. For the purposes of disclosing the present invention, it is considered sufficient to state that each of the keys 217 and 218, is mounted on a corresponding key lever similar to the levers 228, 250, and 252, and when each key is depressed, it actuates a corresponding cam unit which in turn operates the mechanism for effecting the functional operation corresponding to the depressed key. Also, a solenoid actuator 247 is connected to each of the key levers supporting the keys 217 and 218 and when energized effects the operation of the corresponding cam unit in the same manner as when the keys are manually depressed.

Referring particularly to Figs. 8 and 9, it is noted that the typewriter is provided with rib-

bon control mechanism which functions to move an inked ribbon 301 upward and in front of the copy sheet 221 as each type bar 212 is moving toward the platen 219 to effect a printing operation. When printing has been effected and as the type bar is being returned to rest position in the type basket, the ribbon is moved downwardly from in front of the platen so that the typed matter can be readily seen. The ribbon control mechanism disclosed herein is of the same general type as disclosed in U. S. Patent No. 1,937,048, granted November 28, 1933. As is common, the ribbon 301 is threaded through a vibrator or holder 302, and the latter is mounted for limited vertical sliding movement on the type bar guide 240. The vibrator 302 extends downwardly and is pivoted at its lower end to the outer end of a lever 303 which is in turn pivoted at 304 on a fixed frame part 305 of the typewriter. A link 306 is pivoted at its upper end to a midpoint of a lever 303 and at its lower end carries a stud 307 which is mounted for pivotal and sliding movement within an arcuate slot 308 formed in one end of a control lever 309, the latter being pivoted at a midpoint to a fixed stud 311 carried by the typewriter frame structure. The other or forward end of the control lever 309 is connected by a link 313 with an arm 314 fixed to and extending rearwardly from a universal bar or bail member 315. The latter is pivoted on a horizontal rod 316 fixed to a frame part 317 and the arm 314 is provided with a downward extension 318 carrying at its lower end a contact-actuating roller 319. The bail 315 and its attached arm 314 in effect form a bell crank pivoted at a midpoint on the rod 316. The bail 315 extends across the typewriter from side-to-side and the upper forward end thereof is formed as a plate 320 which is in overlying engagement with all of the downwardly projecting arms 321 formed, respectively, on the sub-levers 236 previously described. A pair of normally closed spring blade contacts 323 are fixed to a typewriter frame part 324 and the lower movable blade 325 thereof extends outwardly and beneath the roller 319 and in position to be actuated by the latter.

As explained hereinabove, each sub-lever 236 is an element of a link-and-lever assembly forming an operating connection between a type bar 212 and its related cam unit 233. The sub-levers 236 are each rocked clockwise from the position shown when their related cam units 233 are tripped to effect printing operations of their related type bars. Thus, as each printing operation is begun the depending arm 321 of the operated sub-lever 236 rocks the bail member 315 counterclockwise, and the latter, through the link 313, control lever 309, link 306, and lever 303, moves the vibrator 302 upward so as to place the ribbon 301 in front of the copy sheet 221 where the ribbon will be struck by the type carried by the actuated bar 212. As each type bar returns to the rest position in the type basket, its sub-lever 236 rocks counterclockwise and thereby permits the ribbon-lift bail 315 to return, through the connection just described, the ribbon 301 to the lower or rest position shown in Fig. 8.

Means is provided for selectively printing the character data in either one of two colors. The ribbon 301 is of the bichrome type, for example one having red ink applied to its lower half and black ink to its upper half. As is well known, the color of the printing is determined by the height to which the ribbon 301 is raised for each printing operation. The height to which the rib-

bon is lifted may be varied by changing the position of the pivot stud 307 in the slot 308. With the stud 307 in the extreme forward position shown, the ribbon 301 will be lifted during a printing operation to a position where the upper half or black-ink portion of the ribbon will be in printing position. If the stud 307 is moved to the left-hand or rear end of the slot 308, the effective length of the arm of the control lever to which the stud 307 is connected, is lengthened and, as a consequence, the vibrator 302 will be lifted higher during a printing operation so that the lower or red-ink portion of the ribbon will be placed in printing position.

As will be explained more fully hereinafter, the color of the printing is under the selective control of significant code designations recorded in the tape 10. As shown, in Fig. 9, a solenoid 341 is mounted horizontally on the fixed frame part 324, and the armature 342 thereof is connected through a link 343, bell crank 344 and link 345 with the pivot stud 307. When the solenoid is deenergized, the condition shown, a tension spring 347 connecting a fixed bracket 348 with the bell crank 344 urges the link 345 and stud 307 to the forward or right-hand end of the slot 308, the position shown in Fig. 8, where, as explained above, the character will be printed in black. When the solenoid is energized, the armature 342 thereof, through the link 343, bell crank 344, and link 345, moves the stud 307 to the left-hand end of the slot, where printing in red is effected.

As will be apparent from an examination of Fig. 8, the ribbon-lift bail 315 begins to move almost immediately with the movement of the sub-levers 236 and the latter move as soon as the cams of their related cam units 233 grip the power roller 232 and begin to rotate. Through the depending arm extension 318 and roller 319, the normally closed contacts 323 are opened as soon as the ribbon-lift bail 315 begins to move from the position shown in Fig. 8 at the beginning of each printing operation, and the contacts 323 remain open until the bail 315 is returned to the position shown at the completion of each printing operation. A study of the operation of typewriters of the type disclosed reveals that the length of time extending from the instant each type bar leaves the basket until the instant it is returned to the rest position shown, varies substantially with the different type bars. There is also some variation in time consumed between the time of tripping of the different cam units and the time the cams and their related type bars 212 begin to move and also between the time the bars are returned to the rest position and the time the related cams are reset, the latter differences in time being due to the varying characteristics of the different cam units. However, these latter time differences due to the individual characteristics of the cam units, are relatively small compared with the previously mentioned time differences caused by the individual operating characteristics of the type bars and their associated link-and-lever assemblies for operating them. By way of example, it is noted that in one machine under study, the fastest type bar to operate was out of the type basket the total elapsed time of 35 milliseconds and the slowest bar to operate was out of the basket for 80 milliseconds, and that the fastest cam to operate started moving 20 milliseconds after being tripped and the slowest 45 milliseconds. Thus, in this particular machine there is a total variation in type bar action of 45 milliseconds, and a total

variation in delay between cam tripping and cam movement of 20 milliseconds. The variation in resetting time of the cams was found to be very small, viz., on the order of 10 milliseconds.

Because of the fact that the contacts 323 are opened, in the manner described above, as each type bar 212 leaves the type basket and are closed as each type bar is returned to the basket, it is apparent that the lengths of time the contacts are open during the printing operations vary in direct proportion to the lengths of time required for such printing operations. As will be explained more fully hereinafter, the contacts 323 are in the energizing circuit for the clutch magnet and thereby control the time extending between the beginning of each reading operation where a character representing code designation is sensed and the beginning of the next succeeding reading operation.

The operation of the apparatus thus far described will now be described in connection with the wiring diagram shown in Figs. 12a and 12b. From an examination of these views, it will be noted that all of the control instrumentalities and circuit wires located within the reader 100 are shown diagrammatically in Fig. 12a, and this includes the relay translator mechanism previously referred to herein, and that all of the control instrumentalities and circuit wires mounted on the typewriter are shown in Fig. 12b. For the purposes of simplicity, the circuit wires of the reader which are connected, respectively, by the individual wires within the cable RT (Fig. 1) with corresponding circuit wires in the typewriter are shown as terminating at the right-hand margin of Fig. 12a in plug socket connections, designated, respectively, as R1 to R59, inclusive. The corresponding circuit wires in the typewriter terminate at the left-hand margin of Fig. 12b in plug socket connections T1 to T59, inclusive. It is to be assumed that the plug sockets R1 to R59 are connected, respectively, to the plug sockets T1 to T59, inclusive by the individual cable wires.

As stated above, the relay translator mechanism comprises the series of relays M1 to M6, inclusive, which, during each cycle of operation of the reader, are energized singly or in combination, as a result of the producing of significant signals by the sensing of code hole designations in the record tape. The relay translator shown is a well known mechanism which, in response to the selective energization of its relay magnets in the manner just stated, sets up a number of controlling circuit paths corresponding, respectively, to the code designations sensed. The relays M1 to M6, inclusive, control, respectively, the operation of one or more related transfer contacts which, during each sensing cycle will be transferred, or left at normal position, so that the contacts may be connected in combinational series to condition the just mentioned controlling circuit paths. As shown, the armature of relay M1 operates a pair of contacts M1-1; the armature of relay M2 operates two pairs of contacts M2-1 and M2-2; the armature of relay M3 operates four pairs of contacts M3-1 to M3-4, inclusive; the armature of relay M4 operates eight pairs of contacts M4-1 to M4-8, inclusive; the armature of relay M5 operates sixteen pairs of contacts M5-1 to M5-16, inclusive; and the armature of relay M6 operates thirty-two pairs of contacts M6-1 to M6-32, inclusive. In Fig. 12a, these various relay-controlled transfer contacts are shown in their upper or normal posi-

tion, which is the position they occupy when their related operating relays are deenergized. When any translator relay is energized, all of its related contacts transfer to the lower position.

In Fig. 12a the above mentioned controlling circuit paths are shown as including, respectively, the circuit wires extending from the output terminals of the translator to the plug socket connections R₄ to R₅₉, inclusive. With the exception of plug socket connections T₉ and T₁₆, the plug socket connections T₁ to T₅₆, inclusive, are shown in Fig. 12b as connected, respectively, by individual circuit wires with the solenoids 247 which actuate the character and functional key levers of the typewriter previously described. As will appear more fully hereinafter, the circuit wires extending from T₉ and T₁₆ are connected to relays for controlling the energizing and de-energizing of the color control solenoid 344.

In Figs. 12a and 12b, all switches, solenoids, relays, contacts, and associated parts are shown in the positions they normally occupy with no tape under the sensing gate 21 (Fig. 1) and with both power switches 24 and 224 in open position and with the type basket in its lower case position shown in Fig. 8. A source of alternating current is indicated in Fig. 12a by the lead wires 400 and 401.

As stated previously, both the reader motor RM and the typewriter motor TM are operated when either the power switch 24 or the power switch 224 is closed position. One side of the motor RM is permanently connected to the lead 400, and also one side of the motor TM is permanently connected to the lead 400 by a wire 402, plug socket connections R₅₉ and T₅₉, wire 403, and wire 404. Upon closing of switch 24, the other side of the motor RM is connected thereby to the other supply lead 401 by a wire 408, and the other side of the motor TM is connected to the supply lead 401 by a wire 405, plug socket connections T₅₂ and R₅₂ and wire 409. The closure of the switch 24 also energizes a rectifier transformer 406, one side of the primary being permanently connected to the supply lead 400, and the other side being connected to the wire 408, and through the latter and switch 24 with the other supply wire 401.

With one side of the motors RM and TM and transformer 406 being permanently connected to the lead 400 in the manner just explained, the closing of switch 224 also energizes the motors RM and TM and the transformer 406 as follows: from wire 401, wire 410, plug socket connections R₅₈ and T₅₈, wire 411, the switch 224, a wire 412, wire 413, and wire 405, to the other side of motor TM; and through wire 405, plug socket connections T₅₂ and R₅₂, the wires 409 and 408, to the other side of the motor RM and the other side of the primary of transformer 406.

With the transformer 406 energized in the manner just explained, alternating current is supplied to the input terminals of a rectifier 415. The positive and negative D. C. output terminals of rectifier 415 are connected, respectively, to a plus bus 416 and to a minus bus 417. The opposite sides of the coil of a reader relay 420 are permanently connected with the plus bus 416 and the minus bus 417, so that as long as the rectifier is supplied with alternating current, the relay 420 remains energized. When the relay 420 is thus energized, the armature 423 thereof connects the minus bus 417 to each of wires 431, 432, 433, 434, 435, and 436, which are respectively connected

to the return sides of the six translator relays M₁ to M₆, inclusive.

With a record tape 10 properly positioned under the gate 21 in the reader 100, the contacts 96 are closed by the pin 94 and the apparatus is ready for successively reading and transcribing the code designations in the tape onto the record sheet 221 in the typewriter 200. The tape sensing and feeding operation is started by depressing either the reader start switch 25 or the typewriter start switch 225. The reader start switch 25 is provided with two pairs of spring blade contacts 440 and 441, respectively, the contacts 440 being normally opened and being closed upon depressing the start switch 25, and the contacts 441 being normally closed, and being open when the start switch 25 is depressed. The movable one of the normally open contacts 440 is connected by a wire 442, with the plus bus 416. Thus, when contacts 440 are closed by depressing switch 25, direct current will flow from the plus bus 416 through the wire 442, contacts 440, a wire 443, plug socket connections R₅₅ and T₅₅, a wire 444, the normally closed insert switch 227, a wire 445, plug socket connections T₅₃ and R₅₃, a wire 446, normally closed pick-up contacts 447 of a master control relay 448, a wire 449 to one side of a main coil 450 of such relay 448; and, from the coil 450, through wire 451, the now closed contacts 96, and a wire 452 to the minus bus 417. When the master control relay 448 is thus energized, the armature thereof moves to the right and thereby opens the pick-up contacts 447 and closes a pair of holding contacts 453, the latter being connected directly to the plus bus 416 by a wire 454. The contacts 447 and 453 are of the overlapping type, that is, the holding contacts 453 make before the pick-up contacts 447 break. With the holding contacts 453 closed, direct current will flow through the holding circuit for the main coil 450 which is traced as follows: from the plus bus 416, through the wire 454, contacts 453, wire 449, to the coil 450; and, from the latter, through wire 451, contacts 96, and wire 452, to the minus bus 417.

Contacts 455 also close when master control relay 448 is energized and they thereby condition an energizing circuit for the clutch magnet CM. This conditioned clutch magnet control circuit is established when the start switch contacts 441 are again closed by the operator releasing the start switch 25. The clutch magnet circuit is traced as follows: from the positive bus 416 through the plug socket connections R₅₇ and T₅₁, a wire 456, normally closed relay contacts 350 which as will be explained hereinafter are under the control of elements for effecting carriage return of the typewriter, a wire 457, the normally closed contacts 291 which are actuated by the carriage-return cam as previously described, a wire 458, the normally closed contacts 323 operated by the ribbon-lift bail 314, a wire 439, normally closed contacts 326 which are under the control of elements for effecting tabulating operations of the typewriter and will be explained hereinafter, a wire 459, normally closed contacts 460 of the typewriter start switch 225, wire 461, plug socket connections T₅₄ and R₅₄, wire 462, the now-closed contacts 455 of the master control relay 448, a wire 463, the now-closed contacts 441 of the start switch 225, wire 464, the clutch magnet CM, and from the latter through a wire 465, the now-closed contacts 96, and wire 452 to the minus bus 417. The clutch magnet circuit just traced directly controls the operation of the

reader in the manner previously explained; i. e., when the clutch magnet CM is energized by the closing of this circuit, the operating shaft 35 of the reader is connected by the clutch 37 to the power shaft 31 and when the clutch magnet CM is deenergized by the opening of the circuit just traced, the arm 47 (Figs. 2 and 6) moves into engagement with the barrel 41 and into the path of projection 46 which functions to disengage the clutch 37 and stop the shaft 35 at home position.

The typewriter start switch 225 is connected in parallel with the reader start switch 25, so that the operation of the apparatus may be started by depressing and releasing the switch 225 in the same manner as just described in connection with the switch 25. As shown, the switch 225 is provided with two pairs of spring blade contacts which are the normally closed contacts 460 mentioned above, and a normally open pair of contacts 461. One contact of the pair of contacts 461 is permanently connected to the D. C. plus bus 416 through the wire 456 and plug socket connections T57 and R57. The other contact of the pair of contacts 461 is connected by a wire 468 and a wire 469 with the normally closed insert switch 227 which, as explained previously in connection with switch 25, is connected to the D. C. minus bus 417 through the wire 445, plug socket connections T53 and R53, wire 446, pick-up contacts 447 of the master control relay 448, wire 449, coil 450, wire 451, contacts 96, and wire 452. Thus, with the apparatus at rest, by depressing the switch 225 to close its contacts 461, and open the contacts 460, a flow path for direct current is established through the pick-up contacts 447 and coil 450 of the master control relay 448, and the latter, when energized, will close its holding contacts 453 and remain energized by the holding circuit established thereby which was previously traced. As explained above, the contacts 455 are closed by the energizing of relay 448 and the clutch magnet circuit is conditioned thereby. When the start switch 225 is released, its contacts 460 again close and the conditioned energizing circuit for the clutch magnet CM is thereby established.

As described previously herein, when the reader shaft 35 commences to rotate, due to the energizing of the clutch magnet CM and the resulting engagement of clutch 37, the tape 10 is first spaced to move a record field into sensing position which is directly above the sensing pins S1 to S6, inclusive, and then the field is sensed by the pins to determine the code hole designation therein. As an example let it be assumed that the record field being sensed bears the code hole designation for the letter character "Y" which, as shown in Fig. 13, comprises code holes in positions 1, 3, and 5. As shown in Fig. 7, and as previously explained, the sensing of the 1-3-5 code hole designation will result in the sensing pins S1, S3, and S5 moving upward through the code holes in the tape to close the contacts C1, C3, and C5, respectively. The contacts C1, C3, and C5 will close at approximately 130° of the revolution of shaft 35 to condition signal circuits connected in parallel, and will remain closed until 325°, and the D. C. common contacts 104 are closed by the cam 102 at 142° to establish such signal circuits and are opened again at 311°. With the contacts C1, C3, and C5 closed, and with the D. C. common contacts 104 closed, the signal current will flow from the D. C. positive bus 416 through cam contacts 104, the contacts C1, C3, and C5 in par-

allel, and through signal wires 471, 473, and 475 to translator relay magnets M1, M3, and M5, respectively, and from the latter through wires 431, 433, and 435, respectively, the closed contacts of read relay 420, to the D. C. minus bus 417. With the translator relay magnets M1, M3, and M5 thus energized by the producing of a signal corresponding to the 1-3-5 code designation, their respective relay contacts are transferred to their lower positions. As the relays M2, M4, and M6 remain deenergized, their related transfer contacts will remain in their normal upper positions.

With the transfer contacts of the translator 15 in the position just stated, and when the cam 106 on the reader shaft 35 closes the A. C. common contacts 108 at 170° of the revolution of shaft 35, alternating current will flow through the controlling circuit flow path established by the translator contacts, to the solenoid 247 controlling the key lever 228 for the character "Y" on the typewriter, and, thereby, effect the tripping of the related cam unit 233 and the resulting operation of the related type bar 212 in the manner previously explained. Assuming the type basket to be in its lower case position, the energizing of the solenoid 247 as just explained will result in the lower case character "Y" being printed on the sheet 221. The closed A. C. circuit path for energizing the solenoid 247 is traceable as follows: from the A. C. supply lead 400, a wire 477, contacts 108 now closed, a wire 478, contacts M1-1 in the lower position, a wire 479, contacts M2-2 in the position shown, a wire 480, contacts M3-3 in the lower position, a wire 481, contacts M4-6 in the position shown, a wire 482, contacts M5-11 in the lower position, a wire 483, contacts M6-22 in the position shown, a wire 484, the plug socket connections R35 and T35, a wire 485, solenoid 247 for actuating the type bar carrying the character "Y," a wire 486, and if the power switch 24 is closed, through the wires 413 and 405, plug socket connections T52 and R52, the wire 409, switch 24 to the A. C. supply wire 401. If instead, the switch 45 224 is closed, the circuit will include the wire 412, switch 224, wire 411, plug sockets T58 and R58, and wire 401.

At approximately the same time the type bar 212 carrying the type for the letter "Y" is moved 50 from its position of rest in the type basket by the link-and-lever operating connection with its related cam unit 233, the contacts 323 are opened by the ribbon-lift bail 315 being operated by the sub-lever 236 which forms a part of such link-and-lever connection. As explained above, the contacts 323 are in the clutch magnet circuit and the opening of such contacts, as just noted, will deenergize the clutch magnet CM and thereby cause the outer end of arm 47 (Figs. 2 and 6) to move into engagement with the clutch barrel 41 and into the path of movement of extension 46 of clutch disengaging arm 45, with the result that if the clutch CM is not again energized and the arm 47 thereby moved out of the way of the extension 46 before the reader shaft 35 reaches its zero or home position, the reader shaft 35 will become declutched from the power shaft 31 and come to rest at the home position. The contacts 55 323 are closed by the ribbon-lift bail at approximately the same time the type bar 212 returns to rest position in the basket. Thus, the clutch magnet can not again be energized to start the next succeeding cycle of the reader shaft 35 until the type bar operated in the present cycle has returned to the basket. It is, therefore, apparent 60 70 75

that with the ribbon-lift ball contacts 323 in the clutch magnet circuit there can be no interference in the type bar movement in successive operating cycles.

With the reader shaft 35 operating at a uniform speed, the time consumed from the beginning of each of the operating cycles up to and including the tripping of a cam unit, is about the same for every cycle in which a character representing code designation is sensed. As stated above, there is a relatively small variation in time consumed between the tripping of the different cam units and the point where their respective cams to begin to move, such variation being about 26 milliseconds in the particular example given. Also, there is a negligible variation between the time the type bars are returned to rest and the resetting of their related cams, viz., on the order of 10 milliseconds in the particular example. However, as was also explained above, it has been determined that the total elapsed time the type bars are out of the type basket varies materially according to the structural and operating characteristics of the different type bars and of their respective link-and-lever connections with their related cams, the total variation in the example noted above being on the order of 45 milliseconds.

In order to obtain the maximum typing speed with the apparatus illustrated, the speed of the reader shaft 35 should be such that the fastest type bar to operate will reclose the contacts 323 and thereby reenergize the clutch magnet at approximately the same time the reader shaft completes a revolution. With such an arrangement, there will be a delay between succeeding revolutions of the reader shaft when any of the slower type bars are operated, the amount of such delay varying in direct proportion to the speed characteristics of such slower type bars. Thus, with the contacts 323 opening at the beginning and reclosing at the end of each printing operation, the elapsed time between the beginning of each operating cycle of the reader in which a character representing designation is sensed and the beginning of the next succeeding operating cycle of the reader, varies as an increasing function of the time consumed by the printing operation of the type bar corresponding to such sensed code designation.

In previous constructions, wherein the reader shaft remains clutched to the power shaft during successive cycles in which character designations are sensed, the speed of the reader shaft must be such that there will be sufficient time during each cycle for the slowest type bar to be operated. Thus, with the latter structures the typing speed is limited by the slowest type bar. In the structure disclosed herein, the overall typing speed is materially greater because the speed is controlled by the operating characteristics of the individual type bars.

As is disclosed fully in my said copending application, when a code designation is sensed which represents either the carriage-return, tabulating, or the back-space operation, provision is made for stopping and holding the reader shaft 35 at home position while such functional operations are being effected by the typewriter and for resuming the sensing operations upon a completion of such functional operation. From an examination of Fig. 12b, it will be noted that each of the key lever actuating solenoids 247 for effecting these three last-mentioned functional operations is connected to a circuit wire 491, and

that the latter is in turn connected through a wire 492, plug socket connections T51 and R51 and the wire 490 with one input terminal of a rectifier 493. The other input terminal of the rectifier 493 is connected by the wire 409 and switch 24 with the A. C. supply wire 401. If the switch 224 is closed instead of switch 24 such other input terminal of rectifier 493 is connected to supply wire 401 through plug sockets R52 and T52, wire 405, wire 413, wire 412, switch 224, wire 411, plug sockets T58 and R58, and wire 410.

Thus, when the code designation corresponding to either the carriage return, tabulating or back space operation is sensed, and the translator is adjusted thereby to condition a controlling circuit through the solenoid 247 corresponding to the sensed code designation, the closing of the A. C. common contacts 108 will energize such corresponding solenoid 247 and will connect the input terminals of rectifier 493 across the A. C. supply line. One D. C. output terminal of the rectifier 493 is connected by a wire 494, relay contacts 495 and wire 496 with one side of a bucking coil 497 of relay 448, and the other side of the coil 497 is connected with the other D. C. output terminal of the rectifier. With relay 448 energized, the contacts 495 are closed. Consequently, the just described closing of A. C. common contacts 108 will result in the energizing of bucking coil 497. The coils 497 and 450 are oppositely wound, and the coil 497 is of sufficient strength to overcome the coil 450 and cause relay 448 to drop out and thereby open its holding contacts 453. The contacts 495 also drop out and break the circuit through the bucking coil 497. The contacts 455 in the clutch magnet circuit also open to deenergize the clutch magnet CM and thereby stop further sensing operations. The pick-up contacts 447 close, but the main coil 450 cannot be energized again until other normally open contacts in the pick-up circuit are closed.

As described hereinabove, when the carriage-return designation is sensed and the solenoid 247 corresponding thereto is energized, the cam unit 253 is actuated and is held in its actuated position by a toggle lever-and-link arrangement until the carriage is returned and the toggle arrangement is broken and restored to normal condition by a lever arm 269 (see Fig. 10). As explained previously, when the carriage-return cam unit 253 is actuated, the arm 285 moves to the left as viewed in Figs. 10 and 12b and thereby closes contacts 290 and 292 and opens contacts 291, and when the carriage-return operation is completed, the arm 285 is returned to its inactive position shown, and the contacts 290 and 292 move back to the open position shown and contacts 291 back to their closed position.

When the contacts 292 are closed by the arm 285, as just explained, a full wave dry plate rectifier 351 is thereby connected across the A. C. supply source by a circuit traced as follows: from the A. C. supply wire 400, wire 402, plug sockets R59 and T59, wire 403, wire 404, a wire 352, contacts 292, wire 353 to one input terminal of rectifier 351; and, from the other input terminal of rectifier 351, through a wire 354, wire 436, wire 413, wire 405, plug sockets T52 and R52, wire 409, and switch 24 to the other A. C. wire 401. If the switch 224 is closed, instead of 24, the circuit will include the wire 412, switch 224, wire 411, plug sockets T58 and R58, and wire 410. With the rectifier 351 thus connected across the A. C. source, a relay 355, which is connected

across the output terminals of the rectifier, is energized. The energized relay 355 opens its relay contacts 350, previously described as being in the clutch magnet circuit.

Thus, when the carriage-return code designation is sensed, the master control relay 448 is dropped out with the energizing of the carriage return solenoid 247 and the energizing circuit for the clutch magnet is opened by the contacts 455 and also by the relay contacts 350. When the contacts 290 are closed by the arm 285, they establish a pick-up circuit for the main coil 450 of relay 448 through the now closed pick-up contacts 447. This pick-up circuit is as follows: from the D. C. plus bar 416, plug sockets R57 and T57, wire 456, contacts 290, wire 469, insert switch 227, wire 445, sockets T53 and R53, wire 446, pick-up contacts 447, wire 449, main coil 450, wire 451, contacts 96, and wire 452 to the minus bus 417. The relay 448 is thereby again picked up and is held by its hold contacts 453, as before, and its contacts 455 in the clutch magnet circuit close, but the latter circuit is not closed as contacts 291 are still open and as contacts 292 are still closed, and relay contacts 350 are thereby held open. When the carriage-return operation is completed and the contacts 291 again close and the contacts 292 again open to de-energize relay 355 and thereby permit its contacts 350 to close, the clutch magnet CM is energized and a new cycle of operation of the reader begins.

It is noted that in my said copending application, the carriage-return cam unit controls the operation of only one pair of contacts in the clutch magnet circuit and that such contacts are practically the same as the contacts 291 disclosed herein. The reason for including herein in the clutch magnet circuit, the additional relay operated contacts 350, is a safety measure to assure that the clutch magnet will not become energized before the carriage has fully returned to begin a new line of typing. The relay 355 and its contacts 350 delay the reclosing of the clutch magnet circuit, after the carriage-return cam arm 285 permits the contact assembly 288 to assume its normal position, by an amount equal to the time it takes the relay 355 to become de-energized. It has been found that this amount of delay is enough to prevent an accidental premature closing of the clutch magnet circuit before the carriage is fully returned. The contacts 291 are retained as they assure the opening of the clutch magnet circuit without delay at the beginning of a carriage-return operation.

When the typewriter begins a tabulating operation the contacts 326 in the clutch magnet circuit are opened by an element of the typewriter and contacts 327 are closed. Thus, when the code designation representing a tabulating operation is sensed, the typewriter carriage is tabulated and the master control relay 448 is dropped out by the energizing of the bucking coil 497, and the clutch magnet circuit is opened both by contacts 326 and 455. The closing of contacts 327 connects the wires 456 and 469, the same as contacts 360, and they thereby establish the pick-up circuit which was traced above for master control relay 448. The relay 448 is held energized by its contacts 453, and when the tabulating operation is completed and the contacts 326 again closed, the clutch magnet circuit is again established and cyclic reading operations are resumed.

When a back-space code designation is sensed, the typewriter is caused to back space and the

master relay 448 is dropped out due to the energizing of the bucking coil 497, and the clutch magnet circuit is opened by relay contacts 455, as before. However, as a back space operation only requires a relatively short period of time to be completed, the relay 448 is immediately picked up again and held and the clutch magnet circuit restored to the contacts 455. The latter is effected by contacts 310 connecting wires 456 and 469, such contacts 310 being closed by a typewriter element which moves as a result of a back-space operation as explained in said copending application.

The operation of the reader 100 may be manually stopped by depressing either stop switch 26 or 226. One side of switch 26 is connected directly to the A. C. supply wire 400 and the other side of switch 26 is connected to the other A. C. supply wire 401 through a wire 425, a wire 426, the rectifier 493 and wire 409 and switch 24. One side of stop switch 226 is connected to the A. C. supply wire 400 through the wires 404, 403, plug sockets T59 and R59, and wire 402, and the other side of switch 226 is connected to the other A. C. supply wire 401 through the wires 491 and 492, plug sockets T51 and R51, the wires 490, the rectifier 493, and the wire 409 and switch 24. Thus, when either switch 26 or switch 226 is depressed, the rectifier 493 is connected across the A. C. supply line and the bucking coil 493 is thereby energized to drop out the master control relay 448 and thereby open the clutch magnet circuit and stop the reader. Reading operations can then be resumed only by depressing either of start switches 25 or 225 to pick up the master control relay, as previously described.

As stated hereinabove, a further feature of the present invention is to provide for controlling the color of the printing by code designations recorded in the tape. In response to the sensing of the "red" code designation in the tape 10, shown in Fig. 13 as being a code hole in the number 2, 5, and 6 code positions, the relay translator of Fig. 12a is adjusted in the manner previously explained to condition a controlling circuit path therethrough and including the terminal circuit wire 361, plug socket connections R16 and T16, wire 362, relay 363, wire 364, normally closed relay contacts 365, a wire 366, and the previously described common return wire 486 for the solenoids 247 which as explained is connected to the A. C. supply wire 401 either through switch 24 or switch 224. When this conditioned circuit path is closed by the cam 106 closing A. C. common contacts 108 which connect the A. C. supply wire 400 to the input wire 478 of the translator, the relay 363 is energized and thereby closes its hold contacts 367 and a second pair of contacts 368. The hold contacts 367 connect one side of the relay 363 directly to the A. C. supply wire 400 through the wire 404, wire 403, and plug socket connections T59 and R59. As the other side of relay 363 is already connected to A. C. supply wire 401 through the wire 364, relay contacts 365, and wires 366 and 486, the relay 363 is held energized by the closing of its hold contacts 367. The now closed relay contacts 368 energize the solenoid 341 by a D. C. circuit traced as follows: from the positive bus 416, plug socket connections R57 and T57, the wire 456, the solenoid 341, a wire 370, the relay contacts 368 now closed, a wire 371, and plug socket connections T56 and R56 to the negative bus 417.

As explained hereinabove, the energizing of the solenoid 341 results in the moving of the pivot

pin 307 to the left-hand end of slot 308 (see also Fig. 8), with the result that when a character cam unit 233 is tripped in a subsequent cycle, the control lever 309 will be rocked by the ribbon-lift bail and the vibrator or holder 302 will thereby be lifted to a point where the red-ink part of the ribbon will be placed in printing position. The printing in red ink will continue until the "black" code designation is sensed.

As shown in Fig. 13, the "black" code designation comprises a code hole in the number 3, 5, and 6 code positions. The sensing of the 3-5-6 code designation results in the translator being adjusted, in the manner previously explained, to condition a controlling circuit path through the translator corresponding to such sensed designation and including the terminal circuit wire 375, plug socket connections R9 and T9, a wire 376, a relay 377, and the wires 366 and 480 described hereinabove as being connected to the A. C. supply wire 401 through either the switch 24 or 224. It will be apparent that when A. C. common contacts 108 are closed, later on during the cycle, the conditioned controlling circuit path just identified will be connected thereby to the other A. C. wire 400 and the circuit will be completed. The closing of this circuit will energize the relay 377 which will open its contacts 365 in the holding circuit for relay 363. The relay 363 will thereby be deenergized and open its hold contacts 367 and its contacts 368 which were described above as being in the energizing circuit for solenoid 341. When A. C. contacts 108 are opened later on in the cycle the energizing circuit for relay 377 will be broken and the contacts 365 will return to their normally closed condition. The relays 377 and 363 and solenoid 341 will then be in the deenergized condition shown in the drawings. As explained above, when solenoid 341 is deenergized the spring 347 (Fig. 9) will move the pivot pin 307 back to its right-hand position in the slot 308 as shown in Fig. 8, which is the adjusted position for effecting printing in black ink.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In record-controlled printing apparatus, the combination of cyclically operable reader mechanism for successively sensing data-representing designations recorded in a record sheet, said reader mechanism comprising a rotatable reader shaft, each revolution of which corresponds to an operating cycle, means operated by said reader shaft and during each revolution thereof for spacing said record sheet to bring a data-representing designation into a sensing position, and means operated by said reader shaft during each revolution thereof for sensing the data designation occupying said sensing position; printing means comprising a plurality of character type members selectively operable to effect printing on a copy sheet; means controlled by said reader shaft and acting in response to the sensing of each designation representing a character, for effecting a printing

operation of the corresponding character type member; a continuously rotating power shaft; a one-revolution clutch operable, when engaged, to connect said power and reader shafts for one

5 revolution and then become disengaged; and control means operable upon the beginning of each character printing operation, to prevent operation of said clutch to effect the next operating cycle of said reader mechanism and operable upon the completion of each said character printing operation, to provide for the operation of said clutch to effect the next operating cycle of said reader mechanism.

2. In signal-controlled printing apparatus, the 15 combination of cyclically operable mechanism for successively producing character-representing signals, there being one signal produced during an operating cycle, and said mechanism comprising an operating shaft, each revolution of 20 which provides an operating cycle, and said operating shaft occupying a home or start position while at rest; a continuously rotating power shaft; clutch means adjustable to an effective and to an ineffective condition and operable, when rendered effective with the operating shaft at its home position, to connect said power and operating shafts so as to drive the operating shaft for one revolution, and operable when in ineffective condition as said operating 25 shaft approaches its home position, to disconnect said shafts and stop said operating shaft at its said home position; printing means comprising a plurality of members carrying character type and selectively actuatable to effect 30 printing on a copy sheet; means responsive to the producing of each character signal for effecting a printing operation of the corresponding type member, and each said printing operation being initiated during the revolution of said shaft in which the corresponding signal is produced; and means responsive to each printing operation and effective to adjust said clutch means to its ineffective condition at the beginning of each printing operation and to adjust 35 said clutch means to its effective condition at the end of each such printing operation.

3. In signal-controlled printing apparatus, the 40 combination of cyclically operable mechanism for successively producing character-representing signals, there being one signal produced during an operating cycle, and said mechanism comprising an operating shaft, each revolution of which provides an operating cycle, and said operating shaft occupying a home or start position while at rest; a continuously rotating power shaft; clutch means adjustable to an effective and to an ineffective condition and operable, when rendered effective with the operating shaft at its home position, to connect said 45 power and operating shafts so as to drive the operating shaft for one revolution, and operable when in ineffective condition as said operating shaft approaches its home position, to disconnect said shafts and stop said operating shaft at its said home position; a typewriter including a platen for holding a copy sheet and plurality of type bars, each bar being effective, when actuated, to move from a position of rest into printing engagement with the copy sheet 50 and then return to its position of rest; means responsive to the producing of each character-representing signal for actuating the type bar corresponding thereto and in such a manner that movement of the actuated type bar is commenced 55 during the same revolution of said operating

shaft as when the corresponding signal is produced; and means controlled by the actuation of each type bar and operable to adjust said clutch means to its said ineffective condition as each said type bar leaves its position of rest and to adjust said clutch means to its said effective condition as each said type bar returns to its position of rest.

4. In signal-controlled printing apparatus, the combination of cyclically operable mechanism for successively producing character-representing signals, there being one signal produced during an operating cycle, and said mechanism comprising an operating shaft, each revolution of which provides an operating cycle, and said operating shaft occupying a home or start position while at rest; a continuously rotating power shaft; clutch means adjustable to an effective and to an ineffective condition and operable, when rendered effective with the operating shaft at its home position, to connect said power and operating shafts so as to drive the operating shaft for one revolution, and operable when in ineffective condition as said operating shaft approaches its home position, to disconnect said shafts and stop said operating shaft at its said home position; printing means comprising a plurality of members carrying character type and selectively actuatable to effect printing on a copy sheet; means responsive to the producing of each character signal, for effecting a printing operation of the type carrying member corresponding thereto and such printing operation being commenced during the same revolution of said shaft as when the corresponding signal is produced; and means responsive to printing operations of said type members and controlling the adjustment of said clutch means to provide a time delay between the end of each operating cycle in which one of such printing operations is commenced and the next succeeding operating cycle, which delay varies in amount as an increasing function of the time required to effect said printing operation.

5. In signal-controlled printing apparatus, the combination of cyclically operable mechanism for producing in succession signals representing, respectively, character data in accordance with a predetermined code system and said mechanism including a cycle control member movable the same amount during each cycle and at a predetermined time rate and means operable by said member during its said movement to produce a signal; printing means comprising a plurality of character type members selectively operable to effect printing on a copy sheet; means responsive to the producing of each character representing signal and operated by the movement of said cycle control member, during the cycle in which the signal is produced, for effecting a printing operation of the character type member corresponding to such signal; a device operable when rendered effective to provide for the successive cyclic operations of said cyclically operable mechanism; and means for controlling the operation of said device in accordance with the duration of said printing operations and effective upon the initiation of a printing operation during an operating cycle of said cyclically operable mechanism to render said device ineffective to provide for the next succeeding operating cycle, and effective upon the completion of said initiated printing operation to render said device effective to provide for said succeeding operating cycle.

6. In signal-controlled printing apparatus, the combination of cyclically operable mechanism for producing in succession signals representing, respectively, character data in accordance with a predetermined code system and said mechanism including a cycle control member movable the same amount during each cycle and at a predetermined time rate and means operable by said member during its said movement to produce a signal; printing means comprising a plurality of character type members selectively operable to effect printing on a copy sheet; means responsive to the producing of each character representing signal and operated by the movement of said cycle control member during the cycle in which the signal is produced for effecting a printing operation of the character type member corresponding to such signal; an electrically responsive device effective, when energized, to provide for the successive cyclic operations of said cyclically operable mechanism; and means for controlling the energizing of said device according to the duration of said printing operation and effective upon the initiating of each printing operation, during an operating cycle of said mechanism, to deenergize said device and effective upon the completion of each said printing operation to energize said device again and thereby provide for the next succeeding operating cycle of said mechanism.

7. In record-controlled printing apparatus of the type wherein record fields of a record sheet are successively sensed during successive operating cycles, respectively, and wherein when the designation sensed represents a character, such character is printed on a copy sheet, the combination of sensing means effective, when operated, to sense the record field in a sensing position; spacing means effective, when operated, to move the next succeeding record field of the record sheet into sensing position; printing means comprising a plurality of type members and each said member being operable, when actuated, to move from a rest position into printing engagement with the copy sheet and then return to its rest position; actuating means controlled by said sensing means and operable when a character-representing code designation is sensed, to actuate the type member for printing such character; cycling means operable when rendered effective, to provide a cycle of operation and comprising a cycle control member movable the same amount during each cycle and at a predetermined time rate and effecting during said movement one operation of said sensing means, one operation of said spacing means, and one operation of said actuating means when a character-representing designation is sensed; mechanism for rendering said cycling means effective to provide successive cycles of operation; and means responsive to the operation of each type member and controlling the operation of said mechanism so that the length of time between the beginning of each operating cycle wherein a character designation is sensed and the beginning of the next succeeding operating cycle varies as an increasing function of the time consumed by the operation of the type member corresponding to said sensed character designation.

8. In record-controlled printing apparatus of the type wherein record fields of a record sheet are successively sensed during successive operating cycles, respectively, and wherein when the designation sensed represents a character, such character is printed on a copy sheet, the combination of sensing means effective, when operated, to

sense the record field in a sensing position; spacing means effective, when operated, to move the next succeeding record field of the record sheet into sensing position; printing means comprising a plurality of type members and each said member being operable, when actuated, to move from a rest position into printing engagement with the copy sheet and then return to its rest position; actuating means controlled by said sensing means and operable when a character-representing code designation is sensed, to actuate the type member for printing such character; cycling means operable when rendered effective, to provide a cycle of operation and comprising a cycle control member movable the same amount during each cycle and at a predetermined time rate and effecting during said movement one operation of said sensing means, one operation of said spacing means, and one operation of said actuating means when a character-representing designation is sensed; mechanism for rendering effective said cycling means to provide successive cycles of operation; and means operable, upon the beginning of a printing movement of each said type member from its rest position, to disable said mechanism, and operable, upon each said type member being restored to its rest position, to restore said mechanism to its operative condition.

9. In apparatus of the type wherein a typewriter is automatically operated in response to the successive sensing of character representing designations recorded in record fields of a record sheet, the combination of a typewriter including a platen for holding a copy sheet and a plurality of type carrying bars, each bar being effective, when actuated, to move from a position of rest into printing engagement with the copy sheet and then return to its position of rest; means for sensing a record field of said record sheet to determine the presence of a designation; means

for spacing said record sheet to bring the next record field into sensing position; means responsive to the sensing of each designation representing a character, to actuate the type bar corresponding thereto; cyclically operable mechanism operable during each operating cycle to effect an operation of said sensing means, an operation of said record spacing means, and an operation of said type bar actuating means; an electrically responsive device operable, when rendered effective, to provide for the operation of said cyclically operable mechanism; electrical circuit means for controlling the operation of said cyclically operable mechanism and including a pair of contacts operated in response to the actuation of said type bars and in such a manner that as each actuated type bar leaves its position of rest during one operating cycle, said contacts are operated to render said device ineffective to provide for the operation of said cyclically operable mechanism for the following cycle, and as each type bar returns to its position of rest, said contacts are operated to render said device effective to provide for the operation of said cyclically operable mechanism for such following cycle.
